UNITED STATES PATENT OFFICE

2,273,918

CONTAINER AND PART THEREFOR

Philip Zalkind, New York, N. Y.

Original application October 19, 1935, Serial No. 45,715. Divided and this application September 29, 1939, Serial No. 297,030

6 Claims. (Cl. 45—77)

My invention is a true division of application Serial No. 45,715, filed October 19, 1935, Patent No. 2,200,319, issued May 14, 1940, and relates to collapsible and/or folding containers; and more particularly to novel construction of drawers and the like of this class and novel construction of the parts with which said drawers and the like coact to facilitate movement of said drawer relative to said coacting parts.

In the movement of the drawers in and out of the container in which the drawer is adapted to operate, it is desirable that as much freedom of movement as possible shall be obtained. The patent application of which this is a division was a continuation in part of my copending application Serial No. 693,841, filed October 16, 1933, Patent No. 2,233,906, issued March 4, 1941, in which I have shown novel construction for facilitating the movement of a drawer in a collapsible casing, and of my copending application Serial No. 739,962 filed August 15, 1934, Patent No. 2,159,069, issued May 23, 1939, in which I have shown novel construction for facilitating the movement of a drawer in a folding or collapsible cabinet.

In the aforesaid applications, I have shown a substantially flat bottom drawer of fibrous sheet material with novel wheel and track construction. This construction is generally very efficacious in reducing the friction between the drawer and the container, but I have found that with certain drawer loadings, the drawer bottom will sag or bow an amount to permit the drawer bottom to make contact with the bottom of the casing unless the wheels and tracks or fails are so mounted as to hold the drawer some distance above the bottom of the subjacent part. If the drawer bottom should sag under loading a sufficient amount to come into contact with the subjacent part, the full benefit of my anti-friction mounting cannot be obtained.

I have found that where it is expected to load the drawer in such a manner that, without a special construction, the drawer would rub on the subjacent part when loaded, I may provide means in the construction to eliminate such action.

Moreover, I have found that I may combine various parts of the anti-friction member with reinforcing or connecting members and thus obtain an economy of construction through such combination of parts. I have also found that other economies of construction may be attained through certain novel rearrangement of parts which expedite the manufacture of my novel construction.

Accordingly, objects of my invention are to provide novel apparatus for and methods of moving drawers into and from its container on wheels or rollers; novel apparatus for and methods of mounting collapsible drawers to be moved on wheels or rollers from and into a collapsible container; tracks secured to the container and/or the drawer and rollers or wheels cooperating with said tracks for providing a maximum freedom of movement of the drawer with respect to its container; novel drawer construction to reduce sagging of the drawer bottom upon the subjacent part; tracks combined with reinforcing and/or connecting members; improved construction affecting manufacture.

There are other objects of my invention which together with the foregoing will appear in the detailed description following in connection with the drawings in which:

20 Figure 1 is a perspective view showing a drawer having wheel and track suspending means.

Figure 2 is a perspective view, partly broken away, showing the front end of a drawer and casing with wheels mounted on the bottom of the drawer for supporting same.

Figure 3 is a perspective view of the wheels and a portion of the drawer of Figure 2.

Figure 4 is an enlarged perspective view showing one of the wheels of Figure 3.

Figure 5 is a cross-section on the line 5—5 of Figure 4.

Figure 6 is a developed blank for the wheel mounting of Figures 2—5.

Figure 7 is a perspective view showing a bottom pad for the casing, having tracks for cooperating with a drawer with wheels similar to those shown in Figures 2—6.

Figure 8 is a perspective view showing the rear end of a drawer having a wheel mounted in a track member.

Figure 9 is an enlarged perspective view showing the wheel mounting of Figure 8.

Figure 10 is a cross-section on the plane 10—10 of Figure 9.

Figure 11 is a blank for a drawer having a raised bottom and auxiliary longitudinal bottom reinforcements.

Figure 12 shows a front panel for the blank of Figure 11.

Figure 13 is a perspective view showing the rear end of the drawer of Figure 11.

Figure 14 is an enlarged perspective view showing the wheel mounted in rear end of the track member of Figure 13.

Figure 15 is a cross-section of the back of the drawer on the line 15—15 of Figure 13.

In Figure 1, I have shown a form of folding drawer described in detail in my Patent No. 2,233,906 which has already been referred to. In this figure, the drawer 1 comprises the front wall 2, the inner front wall 3, the side walls 4 and 4', the rear wall 5, the inner rear wall 6, the side wall flaps 7 and 7', and the bottom panel 8, together with front wall flaps 9, rear wall flaps 10 and 10', and tabs extending from each end of both of the side wall flaps. This drawer may be folded from a single blank of sheet material and, after folding, is held in assembled position by means of the various flaps and tabs as described in my Patent No. 1,946,516.

This drawer may be used in connection with the collapsible container of the type described and shown in my Patent No. 2,118,011 or my Patent No. 2,200,319. And where necessary, reinforcing strips or tracks may be placed in the bottom of said casings to cooperate with the roller constructions hereinafter described.

In Figures 2 to 7, I have shown a further feature which may be applied to my drawers, comprising wheels secured to the base or floor member thereof for riding on a track in the casing. As shown in Figure 6, a flat member 41 preferably made of metal may be provided with prongs stamped therefrom and may be scored to form a predetermined bending line at 43 and 44. At 45, the metal is punched out forming a pin support at the openings 46 and 47 for a roller when the metal is turned along the scorings 43 and 44 into the form shown in Figures 4 and 5.

A pin 51 having its ends 52 and 53 of reduced diameter protruding through the openings 46 and 47 and provided with the caps 54 and 55 carries the ring 56. Between the rollers 56 and 57, the roller ball bearings 58 are supported for permitting a free rotation of the caster 59. The member 41, after being formed into the shape in Figure 4, is secured to the inner and outer side walls of the drawer by its prongs as shown in Figures 2 and 3, the side of member 41 coming opposite the inner side wall being admitted therein through a suitable slot formed in the bottom wall.

Secured to the base of the casing is a member 43 (Figures 7 and 2) having the dimensions substantially equal to the inner dimensions of the bottom of the casing and having the tracks 49 and 50 formed therein at positions at which the rollers 59 will ride in the tracks. In a further form of my invention, these tracks may be constructed as an inherent part of the base or bottom sections of the casing, as will be described in further detail.

In a further modification, the wheel members similar to those shown in Figures 2 to 7 may be combined with track members on the drawer, and at the same time the track members may be used to reinforce the bottom drawer corners. Such modification is illustrated in Figures 8 to 10.

Such a track may obviously cooperate with a roller on the casing in the manner set forth in my parent application above mentioned.

As shown in Figure 8, the drawer 60 is provided with the track members 61 provided with the track 62 adapted to coat with a wheel mounted upon the inside of a casing. The track member 61 has the prongs 63 and 64 by which it may be attached to the drawer blank, the prongs 63 being applied to the side wall panel and the prongs 64 being applied to the bottom panel of

the drawer blank. The track member 61 is thus adapted to fit partly over the side wall of the drawer and partly over the bottom of the drawer. As applied to the drawer blank the side wall and bottom wall portion are in the same plane, but when the drawer blank is folded into assembled position, the track member 61 is bent on the bending line 65 and forms an angle reinforcement for the drawer.

As shown in Figure 8 and in greater detail in Figure 9, a portion of the track member may be bent to form a channel having the flange 66 adapted to pass through a slot in the bottom of the drawer and to be fastened to the inside of the side wall of the drawer, as for instance by prongs 67.

At this channel shaped portion, the track member 61 has the punched out portions 67, 68 and 69, the latter two openings being shaped to support the axle 70, and the hole 67 being shaped to permit the wheel 71 mounted within the channel portion to extend through the member 61 in order to cooperate with a suitable track, such for instance as that shown in Figure 13 which has already been described.

While in Figure 10, I have shown a wheel with plain bearings, it will be readily understood that a wheel having roller ball bearings as in Figure 5 may be used in connection with the track member of Figures 8 and 9, or that a plain bearing may be used in Figures 2, 3 and 4 in place of the roller bearing shown in Figure 5.

In any event, it should be noted that the members may be true rolling members or not as the specific need demands, and that rollers 58 (cf. Figure 5) may be used as required.

In connection with Figure 7, I have shown that a track member for the casing may be provided on a separate bottom pad. Other types of pad members may, of course, be used as described in my Patent No. 2,200,319.

In Figures 11 to 15 I have shown the use of a plurality of flanges.

In Figures 11, I have shown a blank of sheet material 151 provided with suitable score lines to define the side walls 152, the side wall extensions 153, the rear wall 154, the rear wall extension 155, the bottom panel portions 156; the central bottom flange portions 157, and the bottom side flanges 158. The bottom panel sections 156 are provided with the front flaps 159; and the side wall extensions are provided with the flaps 160 and 161. The slots 162 are provided in the rear wall extension 155 to receive the flaps 160 when the drawer is folded into position. The bottom flanges may be provided with the cut out portions 163 to allow space for a wheel, which may be mounted on the flanges in a manner as will presently be described. The side wall panel 152 is deeper than the side wall extension 153 by an amount substantially equal to the depth of the flanges 158. In this manner, when the blank is folded into position on its score lines, the extra depth of the side walls forms a portion of the flanges of double thickness shown at 158 in Figure 13.

The rear panel 154 may be provided with the wings 164, and the rear panel extension may be provided with the wings 165. These wings, in the folded position of the blank are held in place between the side wall and the side wall extension, and act to hold the rear wall to the side walls.

When the blank is bent on the score lines 166 and 167 a flange is formed running the length

of the drawer and extending downwardly along the center of the drawer bottom. This brings the two panels 156 in edge to edge relationship to form the drawer bottom as is clearly shown in Figure 13. At the same time flaps 159 are brought into abutting relationship as is the flap 168 and the flange panel 169. The panels 157 may be united with each other in any suitable manner. Thus, they may be adhesively united and/or they may be united by the metallic channel 170 which may extend the entire length of the drawer bottom. In a similar manner, the side flanges 158, may be produced by bending the blank on the score lines 171 and 172, and these flanges may be secured in place by the metallic channels 113 which may be provided with track portion 175. Also flaps 168 and the flanges panel 169 may be folded into face to face relationship with the back panel 154 and united therewith, as for instance by the metallic channel 174 as is shown in Figure 15. The blank after the flanges have been bent into place and properly secured, will be substantially the same form as the back member to be used with my metal faced front as described in my copending application entitled Drawer, Serial No. 45,711, and filed October 19, 1935, Patent No. 2,152,676, issued April 4, 1939. Such a metal faced front is indicated in Figure 12. This front may be united with the body flank 151 by inserting the flaps 159 at the front end of the bottom 156 between the back 176 of the front panel and the metallic member 177. The metallic member 177 is then pressed down and clamps the front face to the body member, which forms the completed blank for the drawer which may be shipped in a substantially flat condition to be set up by the user without the need of any tools or additional parts.

As will be seen in Figure 13 and in greater detail in Figure 14, the channel 173 may be cut out as at 178 to accommodate the wheel 179 mounted on the axle 180 and extending below the bottom face of the channel 173, substantially in the same manner as has been described in connection with Figure 9. The openings 163 provided in the flanges, permit the wheel to operate in the plane of the flanges. A proper track may be provided in the casing for each of the wheels on the drawer.

While I have shown the drawer body as being formed from a single blank of material, I may construct the body from a plurality of blanks united with each other at any of the bottom flanges. Thus it may be seen that if the body blank is composed of three separate pieces ending where the score lines 172 are shown in Figure 11, these three pieces would be united into a uniting structure at the flanges 158 by the metallic channels 173.

This invention is obviously capable of many and varied uses. I prefer, therefore, to be limited not by the specific disclosure herein, but only by the appended claims.

I claim:

1. A collapsible drawer and casing therefor, said drawer being adapted to be slidably supported in said casing; said drawer having score lines along the edges thereof along which the walls of said drawer are collapsible into a substantially flat unit; a track member comprising a metallic angle member secured along the bottom edges of said drawer extending longitudinally along the bottom and side of said drawer to form a reinforcing edge therefor; a predetermined bend line formed in said angle member

coinciding with the score lines of said drawer to permit collapse of said drawer; the portion of said metallic member extending along the bottom having a hole for receiving a roller; a bearing secured to the portion of said metallic member extending along the side adjacent to said hole; and a roller mounted on said bearing for permitting rolling movement of said drawer within said casing.

2. A collapsible drawer and casing therefor, said drawer being adapted to be slidably supported in said casing; said drawer having score lines along the edges thereof along which the walls of said drawer are collapsible into a substantially flat unit; a track member comprising a metallic angle member secured along the bottom edges of said drawer extending longitudinally along the bottom and side of said drawer to form a reinforcing edge therefor; a predetermined bend line formed in said angle member coinciding with the score lines of said drawer to permit collapse of said drawer; the portion of said metallic member extending along the bottom having a hole for receiving a roller; a bearing secured to the portion of said metallic member extending along the side adjacent to said hole; a roller mounted on said bearing for permitting rolling movement of said drawer within said casing; and a track extending longitudinally along the bottom wall of said casing in cooperative relation with said last mentioned roller.

3. A track member for the bottom of a drawer, said track comprising a base and a pair of flanges engaging each side of the lower edge of a side wall, and a roller journaled between said flanges and extending through a perforation in said base, one of said flanges being upwardly extended and curved to form a track.

4. A collapsible drawer and casing therefor, said drawer being adapted to be slidably supported in said casing; said drawer having score lines along the edges thereof along which the walls of said drawer are collapsible into a substantially flat unit; a track member comprising a metallic angle member secured along the bottom edges of said drawer extending longitudinally along the bottom and side of said drawer to form a reinforcing edge therefor; the portion of said metallic member extending along the bottom having a hole for receiving a roller; a bearing secured to the portion of said metallic member extending along the side adjacent to said hole; and a roller mounted on said bearing for permitting rolling movement of said drawer within said casing.

5. A collapsible drawer and casing therefor, said drawer being adapted to be slidably supported in said casing; said drawer having score lines along the edges thereof along which the walls of said drawer are collapsible into a substantially flat unit; a track member comprising a metallic angle member secured along the bottom edges of said drawer extending longitudinally along the bottom and side of said drawer to form a reinforcing edge therefor; the portion of said metallic member extending along the bottom having a hole for receiving a roller; a bearing secured to the portion of said metallic member extending along the side adjacent to said hole; a roller mounted on said bearing for permitting rolling movement of said drawer within said casing; and a track extending longitudinally along the bottom wall of said casing

in cooperative relation with said last mentioned roller.

6. A collapsible drawer and casing therefor, said drawer being adapted to be slidably supported in said casing; said drawer having score lines along the edges thereof along which the walls of said drawer are collapsible into a substantially flat unit; an angular metallic member secured along the bottom edges of said drawer extending longitudinally along a portion of the bottom of said drawer and along portions of the sides of said drawer to form a reinforcing

edge for the bottom and sides, each metallic member having parallel flanges engaging each of the surfaces of the side wall to which it is attached; the portion of said metallic member extending along the bottom having a hole for receiving a roller; a bearing secured to the portion of said metallic member extending along the sides adjacent said hole; and a roller mounted on said bearing for permitting rolling movement of said drawer within said casing.

PHILIP ZALKIND.
